APPARATUS AND METHOD OF PUMPING HYDROCARBON LIQUIDS

Filed March 2, 1936

UNITED STATES PATENT OFFICE

2,080,706

APPARATUS AND METHOD OF PUMPING
HYDROCARBON LIQUIDS

William N. Glab, Dubuque, Iowa, assignor to
Morrison Brothers Company, Dubuque, Iowa,
a corporation of Iowa

Application March 2, 1936, Serial No. 66,561

2 Claims. (Cl. 137—21)

The present invention relates to apparatus for use in pumping volatile liquids such as hydrocarbons and the like, said apparatus enabling the practice of the herein described novel method.

5 In the ordinary unloading rack for pumping gasoline from a tank car, it is the present practice to pump the gasoline from the bottom of the car. Under these conditions the gasoline from the top of the car, which is naturally the lightest 10 and the warmest, is therefore the last to be pumped, and is given the longest pull. As a consequence, this heated gasoline, which is almost a vapor, is pulled apart and it becomes very difficult if not impossible to completely pump out 15 the car. The above method is manifestly inefficient and results in the waste of a large amount of gasoline which might be saved by the utilization of my improved apparatus and method.

In its broad concept, the present invention contemplates a double valve arrangement which may 20 be controlled from the exterior of the tank. By closing one side, the gasoline from the top is unloaded first. After approximately one-half of the car has been unloaded, the other side of the 25 valve is closed and the remainder of the gasoline is taken from the bottom of the car.

To this end, a principal object of the present invention is to provide improved apparatus for the pumping of volatile liquids, whereby the 30 pumping may be accomplished with greater efficiency than is now possible with the apparatus now being used.

A further object is to provide a valve arrangement with connections permitting the lighter portion 35 of a volatile liquid in a container to be pumped before the heavier portion thereof is pumped.

A further object is to provide a pumping arrangement for pumping liquid from a container, 40 which includes a plurality of selectable inlets, whereby the liquid may be selectively pumped from different levels of the liquid.

It is also an object to provide an improved method of pumping a volatile liquid from a container, whereby the waste of liquid as in the present 45 method is substantially eliminated.

Other objects and features of the invention will more fully appear from the following detailed description, taken in connection with the 50 accompanying drawing, which illustrates a single embodiment thereof, and in which:

Figure 1 illustrates a sectional view of a conventional tank car having the apparatus of the herein described invention installed therein and 55 by means of which the fluid within the tank car

may be pumped in accordance with the novel method of the present invention; and

Figure 2 is an enlarged sectional view showing the details of the valve mechanism of my invention, together with the connections to the valve. 5

As shown on the drawing:

In the illustrated embodiment of the present invention, there is shown in Fig. 1 a cross section through a conventional tank car 10 which is provided with the conventional type of dome 11 having a top entrance.

The usual type of overhead unloading rack for pumping the volatile fluid from the tank car comprises a system of piping having a swing joint to which there is connected a pipe swing arm as 15 shown at 12. This arm in the usual installation is coupled by means of a wrench coupling as shown at 13 which may be manually operated to connect the swing arm to the suction pipe 14. The suction pipe is the pipe which extends 20 through the dome entrance into the interior of the tank car and is as a rule of sufficient length to extend to the bottom of the tank.

In the present invention instead of terminating the suction pipe at the bottom of the tank car, 25 this pipe is connected into a valve mechanism 15 which is operable through an extension operating rod 16, this rod being positioned parallel to the suction pipe and supported in guide brackets 17 on the suction pipe. The rod 16 is of sufficient 30 length to extend through the dome entrance and a hand wheel 18 is secured to its outer end for manual operation of the valve.

As more clearly shown in Figure 2, the valve 15 consists of a body portion 19 which defines the 35 valve chamber 20.

Communicating with this valve chamber is an upwardly disposed inlet opening 21 which is internally threaded for receiving a threaded end of a tubular inlet extension 22. Directly opposite 40 the inlet opening 21 is a second inlet opening 23, the upper surface of which adjacent the opening forms a valve seat. The valve body at this inlet opening is extended to form an externally threaded tubular connection 24, which in this case is 45 threadedly connected to a bell-shaped strainer fitting 25. This fitting is provided at its flared end with a strainer 26 for straining the entering fluid. In order that this strainer may be spaced above the bottom of the tank and to prevent closing 50 the opening to the strainer fitting, the fitting is provided around its lower periphery with a series of spaced pads or feet 27.

At substantially right angles to the inlet openings 21 and 23 is a lateral outlet opening 28, and 55

the valve body is formed outwardly from the outlet opening in the shape of an L which is internally threaded at 29 to receive a pipe connection, in this case the lower end of the suction pipe 14.

5 The extension fitting 22 has an internal bridge 30 which is internally threaded at its central portion to form a nut for receiving a valve actuating screw 31 which extends longitudinally 10 through the tubular extension 22.

10 Intermediate the ends of this fitting is an outwardly extending peripheral flange portion 32 adapted to abut one side of a gasket 33 which is disposed between the flange 32 and the associated 15 side of the valve body surrounding the inlet opening 21, whereby the joint between the extension fitting 22 and the valve body is sealed.

15 The uppermost end of the extension fitting 22 is internally threaded as shown at 34 for threadedly 20 engaging one end of a pipe 35, this pipe extending around the valve operating mechanism, the rod 16 being connected to the screw portion by a coupling 36.

20 The lowermost end of the fitting 22 is provided with an inwardly extending flange 37 which strengthens the lowermost end of the fitting. Moreover the lowermost end of the fitting is shaped to define a valve seat 38.

25 In the valve chamber 20 is a valve member 39 which is provided with a central socket 40 opening onto the upper surface of the valve member and threaded to receive a bushing 41 by means of which the valve member is swivelly connected to the lowermost end of the operating screw 31, 30 the lowermost end being provided with a head portion 42 so that when the bushing is screwed into place, the head 42 is disposed within the socket 40 and the valve member thereby secured 35 against removal from the operating screw.

30 The upper surface 43 of the valve member, when the valve is moved upwardly will engage the seating surface 38 of the uppermost inlet opening, thereby closing this inlet to the chamber 20.

35 The undersurface of the valve member 39 is provided with a peripheral groove 44 which defines a seating surface 45 adapted to engage the seat at the lowermost inlet opening, when the valve member 39 is actuated downwardly. This action opens the upper inlet opening and closes 40 the lowermost inlet opening so that the inlet of fluid must be through the uppermost inlet opening.

45 The extension pipe 35 as shown in Figure 1 terminates at its upper end at approximately the mid-portion of the fluid within the tank car 10. By manually manipulating the valve wheel 18, it will be evident that the valve member 39 may be moved so as to selectively close either the uppermost or lowermost inlet opening. In practice, 50 the hand wheel 18 would be moved to bring the valve 39 into a position closing the lowermost inlet so that the inlet would be at a point midway of the liquid in the tank car. This liquid being the lightest is pumped first and as soon as the 55 liquid in the car has been drawn to the top of pipe 35, the wheel 18 is then manipulated to close the uppermost inlet and open the bottom or lowermost opening. The pumping then continues

5 drawing fluid from the bottom of the tank car. By this method of operation, it is possible to more completely pump the volatile liquid from the tank car than is possible in the present arrangements.

10 From the foregoing description, it will be apparent that the present invention provides a novel apparatus and method for pumping volatile liquid such as hydrocarbon and the like from a tank car with increased efficiency over the present arrangements, which enables the pumping of the lighter liquid, which is almost a vapor, with a small pull, and thereafter continuing to empty the car of the heavier liquid by pumping from the bottom of the car; and in which the operative 15 parts of the valve and control mechanism are conveniently located so as to enable control of the selectivity of the pumping inlet from the exterior of the tank car.

20 It is of course to be understood that although I have described in detail the preferred embodiment of my invention, the invention is not to be thus limited, but only insofar as defined by the scope and spirit of the appended claims.

25 I claim as my invention:

1. As an article of manufacture, suction means for unloading a tank car or the like having a top entrance opening and adapted to be removably inserted as a unit into the tank through its entrance opening, a main suction conduit of such length as to extend from the bottom of the tank through the entrance opening to the exterior thereof, a second relatively shorter conduit supported on the main conduit in parallel relation, a communicative connection between the insertable end of the main conduit and a point intermediate the ends of the second conduit, a valve for selectively establishing intake through one or the other ends of the second conduit, and a movable valve actuating rod supported on and outside the main conduit of sufficient length to extend to the exterior of the tank, when said means are disposed in operative position in the tank.

30 2. Apparatus for use in removing a liquid from a tank having a top entrance opening, said apparatus comprising a main suction conduit arranged to extend substantially vertically through said opening with its upper end outside the tank and its lowermost end adjacent the bottom of the tank, a housing at the lowermost end of 45 said conduit having adjacently disposed inlet and outlet top openings and a bottom inlet opening in axial alignment with the top inlet opening, means connecting the lowermost end of the main conduit with the outlet top opening, a relatively short conduit connected to the top inlet opening and extending parallel to the main conduit, a valve supported in the housing for selective movement to close one or the other of the inlet openings, a rotatably mounted valve operating rod 50 having a threaded portion operatively associated with a stationary nut, said rod extending axially through the short conduit and through the entrance opening of the tank in parallel relation to the main conduit with its uppermost end 55 outside the tank, and a bracket for supporting said rod from the main conduit.

60 WILLIAM N. GLAB.
